UNITED STATES PATENT OFFICE

ADOLPH ERISMAN, OF PORT RICHMOND, NEW YORK

ADVERTISING DEVICE

Application filed June 1, 1928. Serial No. 282,082.

This invention relates to advertising devices, and more particularly to a window display advertising device of that general type wherein there is provided a structure simulating a book having a hinged or pivoted leaf adapted to be turned or moved through an arc of 180° to display advertising matter on the opposite sides thereof.

It is the primary object and purpose of my invention to provide a device of the above character wherein there is provided a movable member acting upon the hinged book leaf and thermo-electrically controlled means for actuating said member at predetermined time intervals.

It is also another object of the invention to provide a suitable type of snap switch in the circuit of said actuating means, and said means including an operating element for the switch together with a thermo-responsive resistance element in said circuit connected with said operating element to open and close said circuit and automatically actuate said book leaf actuating means.

It is also another object of the invention to provide means whereby the connection between the switch operating element and the thermo-responsive element of the electrical circuit may be readily adjusted so as to vary the intervals of time elapsing between successive operations of the switch and therefore, between the successive operations of the leaf turning means.

It is also a further general object of the invention to provide a device for the above purpose which is simple in its construction, positive and reliable in practical operation, and in which the several parts are very compactly assembled and arranged so that the entire device will occupy a minimum of window space.

With the above and other objects in view, the invention consists in the improved advertising device, and in the form, construction and relative arrangement of its several parts as will be hereinafter more fully described, illustrated in the accompanying drawings, and subsequently incorporated in the subjoined claims.

In the drawings, wherein I have disclosed

one simple and practical embodiment of my invention, and in which similar reference characters designate corresponding parts throughout the several views.

Figure 1 is a front elevation, the major portion of the top or cover of the housing being removed;

Fig. 2 is a vertical sectional view taken on the line 2-2 of Fig. 1;

Fig. 3 is an enlarged detail vertical section through the lower end portion of the device;

Fig. 4 is a detail horizontal section on an enlarged scale taken on the line 4-4 of Fig. 1;

Fig. 5 is a sectional view taken on the line 5-5 of Fig. 1;

Fig. 6 is a horizontal sectional view taken on the line 6-6 of Fig. 3, showing one position of the leaf turning member after operation to move the leaf in one direction;

Fig. 7 is a similar view showing the opposite position of the leaf turning member;

Fig. 8 is a front elevation on a reduced scale; and

Fig. 9 is a sectional view through the housing or casing of the snap switch showing one type of switch mechanism which may be employed.

Referring in detail to the drawings, 5 designates a housing or casing of suitable dimensions preferably formed of sheet metal, the side, top and bottom walls of said housing having in-turned flanges indicated at 6 upon which a front cover plate 7 of tin or other light sheet metal is secured. Upon this cover plate the metal plate 8 is suitably secured and represents two pages of an open book, said plate bearing upon its surface at opposite sides of its center suitable advertising matter. This plate at its upper and lower edges and at its approximate center has spaced tongues 9 struck therefrom and between these tongues the reduced ends of a metal strip indicated at 10 are adapted to be frictionally engaged. To one edge of this strip the plate 11 representing a book leaf is hinged as at 12, said plate likewise bearing on its opposite side faces, suitable advertising matter.

Within the housing or casing 5 the entire

mechanism for turning the hinged leaf 11 in relatively opposite directions at the end of suitable time intervals to display the advertisements carried thereby, is contained. 5 This mechanism includes a member 13 which is pivotally mounted as at 14 upon a suitable supporting bracket 15 fixed to the bottom wall of the casing 5. This member has parts extending at substantially 90° with respect to each other from the pivot 14 and each terminating in an arcuately curved arm 16. These arms are adapted to be moved through aligned openings indicated at 17 in the front plate 7 of the casing and the plate 8 secured 10 thereon which are located at relative opposite sides of the hinge 12 of the leaf 11.

The bracket member 15 is provided at its central portion with a horizontally extending slot having a central curved section 18 and the straight end sections 19 in alignment with each other. The edges 20 of the member 13 extending at right angles to each other are respectively disposed in coinciding relation with one edge of the respective end portions 19 of this slot in the different positions assumed by the member 13.

The member 13 is automatically operated by suitable thermo-electrically controlled means contained within the casing 5. In the 20 embodiment of the invention herein illustrated, this means includes an expandible and contractable resistance wire 21 which is turned around a series of sheaves or pulleys 22 loosely mounted on the shafts 23 mounted in suitable spaced brackets 24 secured to the bottom wall of the casing 5 at the opposite ends thereof.

One end of this resistance wire is fixed as at 25 to a fixed part on one of the shafts 23. 40 The other end of the resistance wire is suitably attached to an insulating piece 26 with which one end of a coil spring 27 is connected, the other end of said spring being attached to one of the brackets 24. Current is supplied from the house circuit through the wires 28 and 29, the wire 29 being connected with the resistance element 21 adjacent its fixed end 25. The other wire 28 is connected with one pole or terminal by a suitable type 45 of snap switch indicated at 30, the other pole of which is connected by wire 31 with resistance element 21 adjacent to its opposite end. As shown in Fig. 9, the switch includes a pivotally movable contact carrying member 32 which in one position is adapted to connect the pole terminals and thereby close the circuit. This member is operated by and is also movable independently of the member 33 which is pivotally mounted within the switch 50 casing as at 34. To this member 33, the upper end of a rod 35 is suitably connected, the lower end of said rod cooperating with the edges 20 of the pivoted member 13 and being movable in the horizontal slot 18—19 of the 55 bracket plate 15.

This rod is connected with the upper strand of the resistance wire 21 by a sleeve of insulating material 36 loosely engaged on said rod and carrying a set screw 37. The upper part of the sleeve is also provided with a slot 38 intersecting the bore thereof and opening on the upper end of the sleeve, said slot at its base being provided with a recess 39 in one side wall. This slot receives the resistance wire strand and upon tightening the set screw 37 against the rod 35, the strand is bent and forced into the recess 39 while the sleeve 36 is thus rigidly secured in any desired adjusted position along the rod 35 in spaced relation to the pivot 34.

The circuit wires 28 and 29 may extend through a suitable outlet bushing indicated at 40 in the back of base wall of the casing 5 for connection with a suitable plug for engagement in a socket or wall outlet. The rear wall of the casing is also preferably provided with a ventilating opening shown at 41 so that the heat generated by the resistance wire 21 may find a free outlet.

The rear wall of the casing may be extended below the bottom wall thereof and provided with suitable supporting members indicated at 42 and to the rear of the casing an adjustable leg or prop 43 is pivotally attached at its upper end as at 44 so as to support the casing in a desired inclined position. To retain the prop 43 in its adjusted position, I may provide the chain indicated at 45 passing through a suitable eye 46 on the prop 43 and having one of its ends permanently attached to the rear wall of the casing, and said casing wall being provided with a hook indicated at 47 with which the chain adjacent to its other end may be connected.

In the operation of the device as above described, in the position of the rod 35 as seen in Figs. 1 and 9 of the drawings, the switch is open. Assuming that this operation has just taken place, and due to the resistance generated heat, the wire 21 has fully expanded while the spring 27 is contracted, as the resistance wire cools, it will contract and gradually reduce in length, thereby pulling upon the spring 27 and expanding the same. The rod 35 is thus also moved to the left from the position shown in Fig. 1, and during the first part of this movement, the lower end of said rod will move freely in the right hand end portion 19 of the slot in the bracket 50 from the position shown in Fig. 7 of the drawings.

The snap switch as shown in Fig. 9 is of the spring toggle type and during this first part of the movement of the rod 35, the movable switch member remains in the open position while energy is being stored in the toggle spring. Continued contraction of the resistance wire, resulting in further movement of the rod 35, then 125

moves the toggle member past the central position so that the spring acts to quickly throw the movable switch member 32 to the closed position which thereby also 5 imparts a quick movement to the lower end of the rod 35 which bears against one of the edges 20 of the member 13. As this end of the rod moves in the curved part 18 of the slot in the bracket member, the member 13 is 10 moved from the position of Fig. 7 to the position shown in Fig. 6 so that one of its arms 13 is moved outwardly through the opening 17 and acts against the pivoted or hinged leaf 11 to move the same through an arc of 15 substantially 45° and from a position in parallel relation to plate 8 to a position in a plane slightly beyond a 90° angle with respect thereto or past the center of gravity so that said hinge leaf 11 will then drop or fall to 20 the dotted line position shown in Fig. 6 of the drawings.

Since the circuit has now been closed, the resistance wire 21 will again expand and progressively with such expansion of the 25 wire, the spring 27 contracts, thus moving the rod 35 in the opposite direction, or towards the position of Fig. 1. In the first part of such movement, the lower end of rod 35 moves to the right in the end portion 30 of the slot in bracket 15 and is engaged with the angularly extending edge 20 of member 13, at which time the spring toggle of the switch operates to move the switch member 32 to the open position, and continue the 35 movement of rod 35 to thereby operate the member 13 in the reverse direction and cause the other of the arms 16 thereof to engage the hinged leaf 11 and turn the same to its former position.

40 These operations are then repeated as above described at the regular intervals of time sufficient to enable the advertising matter on the surfaces of the movable leaf 11 and of the fixed plate 8 to be read by the observer. The length of time elapsing between successive operations of the member 13 may be varied or changed within certain limits by longitudinally adjusting the sleeve 36 along the rod 35 towards or from the pivot 34.

45 From the foregoing description considered in connection with the accompanying drawings, the construction of my improved advertising device as well as the operation thereof and its several advantages in practical use will be clearly understood. It will be seen that by the provision of electrical resistance control means for actuating the leaf turning movement of the kind above described, it is possible to very compactly 50 house or arrange all of the operating parts within a relatively shallow housing or casting so that the device may be mounted and arranged in a relatively small space in a show window for use in connection with display advertising. Also, in view of the very simple

form and construction of the several elements employed, it will be apparent that the device can be manufactured and sold at relatively small cost and will also be positive and reliable in its operation and not liable to get 70 out of order.

I have herein shown and described an embodiment of the invention which I have found to be entirely satisfactory in practical use. Nevertheless, it will be understood that 75 the essential features of my invention may be susceptible of more or less modification in the form, construction and relative arrangement of its various parts, and I therefore, reserve the privilege of resorting to all such legitimate and alternative embodiments thereof as may be fairly incorporated in the spirit and scope of the invention as claimed.

I claim:

1. In an advertising device, in combination with a hinged plate simulating a book leaf, means for turning said plate to expose the opposite side faces thereof including a movable actuating member having parts to bear against the opposite sides of said plate, 80 an operating member for said element, an electric circuit, a switch in said circuit, said operating member connected with the movable element of said switch, and a thermo-responsive resistance in said circuit connected 85 with said operating member.

2. In an advertising device, in combination with a hinged plate simulating a book leaf, means for turning said plate to expose the opposite side faces thereof including a 100 movable actuating member having parts to bear against the opposite sides of said plate, an operating member for said element, an electric circuit, a switch in said circuit, said operating member connected with the movable element of said switch, an expandable and contractable resistance wire in said electric circuit fixed at one of its ends, a contractile spring connected to the other end of said resistance wire, and means adjustably 105 connecting said resistance wire with said operating member.

3. In an advertising device, in combination with a hinged plate simulating a book leaf, means for turning said plate to expose the 110 opposite side faces thereof including a movable actuating element having parts to bear against the opposite sides of said plate, an operating member for said element, an electric circuit, a switch in said circuit, said operating member connected with the movable element of said switch, two spaced series of rotatably supported sheaves, an expandible and contractable resistance wire in said circuit fixed at one of its ends and trained about 115 said sheaves, a contractile spring connected with the other end of said resistance wire, and means connecting said wire with said operating member to move the latter upon 120 125 130

expansion and contraction of said resistance wire and thereby open or close the switch and operate said actuating element.

4. In an advertising device, a casing, a plate secured upon the front of the casing simulating an open book, a second plate pivotally mounted upon said first plate at its center and simulating a book leaf, an element pivotally mounted within the casing and having arms at opposite sides of its pivot to bear against the opposite faces of said pivoted plate and turn the same in opposite directions, an electric circuit, a switch in said circuit mounted within the casing, an operating member connected at one end with the movable switch element and movably engaged at its other end with said pivoted leaf turning element, a contractable and expansible resistance wire in said circuit fixed at one of its ends, guide means for said wire mounted within the casing, a contractile spring connected with the other end of said resistance wire, and means connecting said resistance wire with said operating member to actuate the latter upon expansion and contraction of said wire and thereby open and close said switch and actuate said pivoted leaf turning element.

5. In combination with a device to be operated, electrically controlled operating means therefor including, in combination with an electrical circuit, a snap switch in said circuit, an expansible and contractable resistance wire in said circuit fixed at one of its ends, spaced guide means supporting said resistance wire and permitting of its linear expansion and contraction, a contractile spring directly connected with the other end of the resistance wire, an operating member for said device connected with the movable element of said snap switch, and connecting means between said resistance wire and said operating member to actuate the latter by the expansion and contraction of the resistance wire to operate said device and open and close said switch.

6. In combination with a device to be operated having a movable part, electrically controlled means for operating said device including an electric circuit, a switch in said circuit, a common operating member for said switch and said movable part, and a thermo-responsive resistance in said circuit connected with said operating member.

7. In combination with a device to be operated having a movable part, electrically controlled means for operating said device including an electric circuit, a switch in said circuit, an operating member connected with said switch to periodically open and close the same and also connected with said movable part to alternately move the same in relatively opposite directions upon the opening and closing of the switch, and a thermo-

responsive resistance in said circuit connected with said operating member.

In testimony that I claim the foregoing as my invention, I have signed my name hereto.

ADOLPH ERISMAN.
